UNITED STATES PATENT OFFICE.

CHARLES H. MORGAN, OF WORCESTER, MASSACHUSETTS.

HEATING-FURNACE FOR ROLLING-MILL PLANTS.

SPECIFICATION forming part of Letters Patent No. 416,007, dated November 26, 1889.

Application filed August 31, 1889. Serial No. 322,583. (No model.)

To all whom it may concern:

Be it known that I, CHARLES H. MORGAN, a citizen of the United States, and a resident of Worcester, in the county of Worcester and State of Massachusetts, have invented a new and useful Improvement in Rolling-Mill Plants, of which the following is a specification, accompanied by drawings forming a part of the same and illustrating the nature and essential features of my invention, and in which—

Figure 1 denotes a plan view in section, and Fig. 2 a side view in section, of so much of the plant as is necessary to fully illustrate my invention, the furnaces in Fig. 1 being shown in horizontal sectional view on line X-X, Fig. 2, and Fig. 2 being shown in vertical sectional view on line Y-Y, Fig. 1.

Similar letters refer to similar parts in the different figures.

My invention consists in the employment of a primary furnace wherein the billet is heated, a secondary furnace communicating with the primary furnace and forming a conduit within which the heat of the billet is maintained while passing from the primary furnace to the train of rolls or reducing mechanism, and a train of rolls placed in juxtaposition to the mouth of the secondary furnace and from which the billet is drawn by the rolls; second, in the employment of two or more primary furnaces in connection with a common secondary furnace and a train of rolls in juxtaposition therewith, whereby two or more billets are simultaneously operated upon; third, in a primary furnace in which the billets are heated and a secondary furnace communicating therewith, said primary furnace having an opening through which the billets are admitted to the primary furnace, and an opening in alignment with the passage to the secondary furnace, by which the billets are transferred from the primary to the secondary furnace; fourth, in the employment of a primary and a secondary furnace and a train of rolls, as hereinafter described, the floors of said furnaces having a downward inclination toward the train of rolls in order to facilitate the passage of the billets; fifth, in the employment with the primary furnace in which the billet is heated of a secondary furnace communicating with the pri-

mary furnace, by which the heat of the billet is maintained in passing to the rolls, and having its floor upon a lower plane than that of the primary furnace, forming an offset over which the billet is pushed in its passage from the primary to the secondary furnace; sixth, in providing means by which the billets are fed to the primary furnace, and, seventh, in providing means by which the billets are pushed from the primary to the secondary furnace.

In the accompanying drawings I have shown an arrangement of furnaces whereby two billets are simultaneously operated upon, A A' representing the two primary furnaces shown in sectional view through the reverberatory chambers of each; and B denotes the common secondary furnace communicating by means of the passages C C' with the primary furnaces A A', and having a mouth B', through which the billets are delivered to the rolls H H H, forming, in the present instance, a portion of a continuous rolling-mill, each of the rolls being provided with the grooves b b, whereby two billets can be simultaneously operated upon.

Each of the primary furnaces A A' is provided with openings A² A², through which the billets are admitted to the outer portion a of the floor A⁴, and also with openings A³ opposite the secondary furnace B and in alignment with the passages C C', to allow the billets to be pushed from the primary furnaces into the secondary furnace.

The floors of the furnaces are inclined downward toward the rolls H H, in order to facilitate the passage of the billets, and the floor B² of the secondary furnace B is placed upon a slightly lower plane than that of the floor A⁴ of the primary furnaces A A', forming an offset c, over which the billets are pushed in their entrance into the secondary furnace B, and which serves to check the rearward longitudinal movement of the billets during their manipulation in the secondary furnace B. The billets are entered between the plain rolls D', and by them forced through the openings A² into the furnaces A A' upon the outer portion a of the floors A⁴ A⁴. When sufficiently heated, they are moved upon the floor of the furnace into position between the passages C C' and openings A³, and the push-

rod F is inserted between the grooved rolls D², with its inner end against the end of a billet G, which is forced by the action of the rolls D² through the passages C or C' into the secondary furnace B, where its temperature is maintained, while it is seized by suitable grappling appliances and drawn forward through the mouth B' to the rolls H H, in the usual and well-known manner. The lower roll of each pair of feed-rolls D D is capable of being raised or lowered by means of the hydraulic jack E, or other well-known appliances, whereby the rolls can be rendered inoperative at will, in order to allow the push-rod F to be retracted and the heated billets successively pushed into the secondary furnace, from which they can be simultaneously drawn into the train of rolls.

For the purpose of illustrating my present invention I have shown in the accompanying drawings a Siemens regenerative furnace, having the three reverberating or heating chambers contained in an integral structure; but neither the type of furnace nor the specific form of construction as represented is an essential feature of my invention. Neither do I confine myself to the apparatus as shown and described for the purpose of charging the primary furnaces with billets or for trans-

ferring them to the secondary furnace.

What I claim as my invention, and desire to secure by Letters Patent, is—

1. The combination of a primary furnace or heating-chamber wherein the billets are heated, a secondary furnace or heating-chamber communicating with said primary furnace and forming a continuous passage from said primary furnace to a train of rolls or apparatus for reducing the billets, whereby the temperature of the billets is maintained, and a train of rolls or reducing apparatus placed in close juxtaposition to the mouth of said secondary furnace, substantially as described.

2. The combination, with a heating-furnace and a train of rolls, of a furnace communicating with said heating-furnace and forming a continuous passage from the heating-furnace to the rolls, whereby the temperature of the billets is maintained in their transit from the heating-furnace to the rolls, substantially as described.

3. The combination, with two or more heating-furnaces wherein the billets are heated, and a train of rolls or apparatus for reducing the billets, of a secondary furnace communicating with each of said heating-furnaces, and forming a common passage from the heating-furnaces to the train of rolls or reducing apparatus, whereby the temperature of the billets is maintained in transit from the heating-furnaces to the rolls, substantially as described.

4. The combination of a primary heating-furnace wherein the billets are heated and a secondary furnace communicating therewith, by which the temperature of the billets is maintained in transit to the rolls, said pri-

mary furnace having an opening through which the billets are fed to the furnace, and an opening in alignment with the passage to said secondary furnace, by which the billets are transferred from the primary to the secondary furnace, substantially as described.

5. The combination of a primary furnace in which the billets are heated and a secondary furnace communicating therewith, and forming a passage from said primary furnace to the rolls, whereby the temperature of the billets is maintained in transit to the rolls, said primary furnace having a floor inclined downwardly toward said secondary furnace, to facilitate the transference of the billets from the primary to the secondary furnace, substantially as described.

6. The combination of a primary furnace in which the billets are heated and a secondary furnace communicating therewith, and forming a passage from the primary furnace to the rolls, whereby the temperature of the billets is maintained in transit from the primary furnace to the rolls, the floors of said primary and secondary furnaces being downwardly inclined from the rear of the primary furnace, where the billets are received, to the discharging-mouth of the secondary furnace, substantially as described.

7. The combination, with a primary furnace in which the billets are heated, of a secondary furnace communicating therewith, and forming a passage from the primary furnace to the rolls, whereby the temperature of the billets is maintained in transit to the rolls, the floor of said secondary furnace being upon a lower plane than that of the primary furnace, forming an offset over which the billets are pushed in their entrance to the secondary furnace, substantially as described.

8. The combination, with a primary furnace in which the billets are heated and a secondary furnace communicating therewith, and forming a continuous passage from the primary furnace to the rolls, said primary furnace having an opening through which the billets are fed to the furnace, of a pair of rolls opposite and in juxtaposition to said opening, whereby the billets are fed to the primary furnace, substantially as described.

9. The combination, with a primary furnace in which the billets are heated and a secondary furnace communicating therewith, and forming a passage to the rolls, said primary furnace having an opening in alignment with the passage to said secondary furnace, of a pair of grooved rolls opposite said opening, and a push-rod actuated by said grooved rolls, by which the billets are transferred from the primary furnace to the secondary furnace, substantially as described.

10. In a rolling-mill plant, the combination of two or more primary furnaces in which the billets are heated, a secondary furnace communicating with each of said primary furnaces, and forming a common passage, where-

by the temperature of the billets is maintained in transit to the rolls, a train of rolls capable of rolling two or more billets simultaneously, and placed in close juxtaposition to the mouth of said secondary furnace, whereby the billets are drawn from said secondary furnace by said rolls, and means, substantially as described, by which the billets are successively fed to said primary furnace and transferred

from the primary furnaces to said secondary to furnace, substantially as described.

Signed at Worcester, in the county of Worcester and State of Massachusetts, this 21st day of August, 1889.

CHAS. H. MORGAN.
